JOSEPH DE BONDINI AND ALBRECHT SEEFFELDER, OF CONSTANTINOPLE,
TURKEY.

WICK-HOLDING ATTACHMENT FOR LAMPS.

SPECIFICATION forming part of Letters Patent No. 365,973, dated July 5, 1887.

Application filed November 10, 1886. Serial No. 218,500. (No model.)

To all whom it may concern:

Be it known that we, JOSEPH DE BONDINI, a subject of the King of Italy, and ALBRECHT SEEFFELDER, a subject of the Emperor of Austria, both residents of Constantinople, Turkey, have invented a new and useful Improvement in Lamp-Wicks or Burner-Tips, of which the following is a specification.

The irregular burning of lamps using petroleum or other oils, the flickering of the light, the bad odor which is given out, and the frequent breaking of chimneys are caused largely, if not principally, by defects in the wicks of such lamps. The trimming of the wick is apt to be uneven unless great care is used. There is also an incrustation or carbonization of the wick, which impairs the steadiness and brilliancy of the flame, and in trimming the wick carbonized particles fall into the interior of the burner, where they are apt to obstruct the passage of air to the flame and to give out an unpleasant odor. To overcome these objections, it has been proposed by several inventors to provide burner-tips of asbestos or other incombustible materials, such tips being arranged in contact with the top of the usual wick or other absorbent material, which is used solely for the purpose of drawing up the oil to the burner-tip. Such asbestos-tipped wicks have usually been inclosed in a tube and the flame adjusted by raising or lowering said tube, or by raising or lowering another tube around it. So far as we are aware such incombustible tips have not proved very satisfactory in actual use, since the mineral substances of which they have been formed are not sufficiently absorbent of the oil, and their pores are liable in time to become clogged or choked and their surfaces to become incrusted.

As an improvement on such tips, it has been suggested to employ burner-tips of vegetable material—such as of cotton-wicking bent double, and its folded part shaped by heat and pressure, or of paper treated with fire-proofing salts, and to renew such tips whenever they became incrusted or carbonized. This plan would prove practicable if the construction were such that the renewal of the tips were rendered sufficiently quick and convenient.

It is the object of our invention to provide a construction which shall supply this condi-

tion. To this end we make the burner-tips separate from the wick and unattached thereto, and we provide a retaining device for holding the tip in contact with the wick, consisting of a cap or ring having hooks or fingers which engage the tip, and which cap or ring can be easily slipped over the wick-tube or removed therefrom, so that the operation of replacing a tip is rendered instantaneous.

Figure 1 of the accompanying drawings is a perspective view of our burner-tip for a round or Argand burner. Fig. 2 is a similar view of a tip for a flat burner. Fig. 3 is a perspective view of the retaining-cap for an Argand burner, and Fig. 4 is such a view of the cap for a flat burner. Fig. 5 shows in perspective an Argand burner provided with our invention, and Fig. 6 shows a flat burner so provided. Fig. 7 is a vertical mid-section of an Argand burner, and Fig. 8 a similar section of a flat burner provided with our invention.

Let A designate the usual burner, either flat or round; and B, the usual wick. In the case of a flat burner the wick is held and guided in a flat wick-tube, d, as usual. In the case of an Argand burner the wick is held between an outer tube, d, and an inner tube, e, as usual. In fact, our invention involves no change in the existing construction of ordinary or common lamps to which it is to be applied.

The burner-tip a, two forms of which are shown detached in Figs. 1 and 2, is formed of papier-maché, which is made porous or unsized, so as to be capable of absorbing the oil, and is molded of the same shape as the wick to which it is to be applied. For an Argand wick it is made in the shape of a ring, and for a flat wick it has the form of a straight bar. In either case its thickness should be the same as that of the wick, and it should have a height of four or five millimeters by preference.

The burner-tip, when placed on the wick, should touch it at all points, in order that it may absorb the oil from the wick readily and uniformly. To insure this the wick should be trimmed to a uniform level, so that its top shall conform to the under side of the burner-tip. The burner-tip is then placed on the wick and held in place thereon by any suitable retaining device that will keep it pressed into close contact therewith without interfer-

ing with the adjustment of the wick up or down, in order to regulate the flame. The means that we have devised for this purpose consist of a ring, *b*, of sufficient weight, carrying fingers *c c*, the pointed ends of which are bent over, as shown in Figs. 3 and 4, so that when placed on the burner these points or hooks rest upon the top of the burner-tip, as shown in Figs. 5 to 8. The ring *b* is of any shape—circular, conical, or rectangular—according to the shape of the burner with which it is to be used, and is large enough to pass easily over the wick-tube *d*. The points or hooks *c c* are arranged at intervals all around the burner-tip, so that the latter cannot escape from them. The ring *b* is of metal, having sufficient weight to keep the burner-tip pressed closely against the wick. As the wick is adjusted up or down to regulate the flame, the burner-tip moves up or down with it.

The retaining device shown may be replaced by any other equivalent device which will exert a slight downward tension or pull upon the burner-tip sufficient to hold it in contact with the wick and permit of the adjustment thereof. The tension should be sufficient, that when the wick is lowered the burner-tip will be drawn down with it until its top is flush with the top of the wick-tube, and it should not be so great that when the wick is raised the burner-tip will resist its ascent.

In the use of our invention the burner-tip is simply placed on the wick and the retaining-ring *b* is dropped over it. When the burner-tip becomes incrusted or otherwise needs renewing, it is taken off and thrown away and a new one put on in its place, which is the work of an instant. This renewal of the burner-tip may be done every day, or at less frequent intervals. The burner-tips will be manufactured in standard sizes and sold in

boxes, and being very cheap their use will be both convenient and economical. There is no trimming of the wick, and hence no spoiling of it by irregular cutting. The lamp burns with greater brilliancy and steadiness, and there is much less liability of breaking the chimney. There are, furthermore, no carbonized particles which fall into the burner, and hence no bad odor is given out.

We claim as our invention—

1. In an oil-lamp, the combination, with the wick-tube and wick, of a burner-tip of absorbent material placed on the wick, and a retaining device independent of the wick-tube engaging the burner-tip and constructed to exert a downward tension thereon, whereby the tip is held in contact with the wick without interfering with the vertical adjustment of the latter, substantially as set forth.

2. In an oil-lamp, the combination, with the wick-tube and wick, of an absorbent burner-tip placed on the wick, and a retaining device consisting of a ring constructed to pass over the wick-tube, and a series of hooks carried by said ring and engaging the burner-tip, whereby the weight of the ring holds the burner-tip against the top of the wick, substantially as set forth.

3. A retaining device for burner-tips, consisting of a ring, *b*, shaped to slip over the wick-tube of a lamp, and hooks *c c*, extending upwardly from said ring and pointed inwardly, substantially as set forth.

In witness whereof we have hereunto signed our names in the presence of two subscribing witnesses.

JOSEPH DE BONDINI.
ALBRECHT SEEFELDER.
